UNITED STATES PATENT OFFICE.

THOMAS F. MORRIS, OF WATERFORD, NEW YORK.

SNAP-FASTENER-UPSETTING MACHINE.

1,403,438.

Specification of Letters Patent. Patented Jan. 10, 1922.

Application filed October 30, 1920. Serial No. 420,794.

To all whom it may concern:

Be it known that I, THOMAS F. MORRIS, a citizen of the United States, residing at Waterford, in the county of Saratoga and 5 State of New York, have invented certain new and useful Improvements in Snap-Fastener-Upsetting Machines, of which the following is a specification.

This invention relates to an improvement 10 in snap fastener upsetting machines, in the use of which the respective parts of the male and female portions of the fastener are secured together and to the fabric.

The invention is particularly designed for 15 applying glove fasteners of the snap type, and is constructed with a view to providing an automatic machine wherein the operator is positively safeguarded against injury in the operation of the machine.

20 As is well understood each male and female portion of the snap fastener is made up of two portions or parts, a formed part to be passed through an opening in the glove or other article and rest against one side 25 or surface of the fabric and a washer or equivalent part to rest against the opposite side of the fabric. The operator assembles these parts in position, arranges the assembled parts on the anvil of the machine, and 30 then upsets or otherwise clamps the two parts together in the operation of the machine. In rapid operation it not infrequently happens that the operator will fail to remove the finger applying the final part to 35 the anvil position in time to escape the upsetting die, and injury results.

The present invention entirely obviates the possibility of such injury, by rendering the machine entirely automatic in its action, 40 and holding it against operation until tripped by the operator in reaching for a part of the next fastener part to be subsequently applied. In other words, the operator must assemble a fastener complete for 45 the upsetting operation on the anvil, and then in reaching for the next part of the fastener to be applied in the next glove opening, trips the machine and sets it in operation to upset the fastener parts already 50 on the anvil. The machine automatically stops following each upsetting operation, and cannot be again tripped until the hand of the operator is reaching for another part of a subsequent fastener, which of course

positions the operator's hand entirely away 55 from the machine.

The present machine embodies another safeguard for the same end, in that the upsetting die is carried on a member normally to one side of the anvil position, the die 60 carrier being moved into position under the plunger in the operation of a lever connected through a spring with the carrier, so that if the hand or fingers of the operator are in the way of the carrier, the latter will on contact 65 with the hand or fingers be brought to rest short of the anvil position, so that no actual upsetting operation can take place. Thus the operator is completely safeguarded 70 against injury.

It is admittedly true that in previous hand operated machines of this type, the operator, requiring one hand for pulling the operating lever is entirely safeguarded against injury in this particular, but such types of machines 75 are commercially inefficient, not only owing to their comparative slowness of operation but to the impossibility of securing identical and similar upsetting pressure in each operation, and the consequent liability of improperly applied fasteners. With the improved type of machine, as in the present invention, the operation is automatic, and in addition to the safeguarding features referred to, an exactly identical and similar 85 pressure is applied to the fasteners of a particular type, so that all fasteners are equally and efficiently secured.

The invention is illustrated in the accompanying drawings, in which:— 90

Fig. 1 is a view in elevation partly in section of the improved machine.

Fig. 2 is a side elevation of the same.

Fig. 3 is a section of the machine taken just above the die carrier, showing more 95 particularly the movement of the die carrier to and from operative position.

Fig. 4 is a view in elevation showing the hopper arrangement in relation to the operating plate. 100

The improved machine comprises a framework including a pedestal 1 supported above the operating table, as shown. The pedestal has upstanding spaced members 2 to form a bearing for a shaft 3, on which centrally 105 between the arms is a cam 4, adapted in each revolution of the shaft 3 to reciprocate a plunger 5 guided in the pedestal.

A die carrier is pivotally supported on the framework to swing to and from a position below the plunger, such carrier comprising a block 6, pivotally mounted at its 5 rear end, and carrying a rotatable table 7 at its forward end. The table comprises upper and lower plate sections 8, in which in concentric relation with the pivot of the table is mounted the respective die rods. 10 These rods, which are independently formed at their lower ends for the respective male and female portions of the fastener, are adapted to be moved, through turning of the table into operative position in the carrier, 15 a pin 9 securing the table in fixed position to use the particular die rod desired. The die rods are each spring pressed in the upward direction through springs 10 coiled about the rods and bearing against the lower 20 plate of the table, and an offset or washer on the rod.

The die carrier is operated through a cam 11 on the shaft 3, which is formed as shown to engage the upper end of a lever 12 in 25 each revolution of the shaft, and move such lever on its frame pivot 13 to cause the lower end 14 thereof, through a spring 15, to move the die carrier so that the selected die rod will be positioned beneath the plunger 5.

30 A spring 16 connected to the upper end of the lever and the frame insures that the lever be held in cooperation with and follow the cam, thus a proper operation of the lever in both directions is secured.

35 An anvil 17 is arranged on a lower portion of the main frame below the plunger 5, in position to receive the upsetting action of the die rod actuated by such plunger, this anvil being formed to removably receive 40 anvil-blocks 18 of different forms, as is required in upsetting the male and female parts of the snap fastener.

The anvil blocks 18 rest upon a stiff spring 19, capable of adjustment through a 45 set screw 20 to secure the desired rigidity of movement of the anvil-block and also to position it vertically for the stroke of the die rod.

The shaft 3 is driven from a continuously 50 operated sprocket wheel 21 secured to one member 22 of a clutch, the other member 23 of which is fixed to the shaft. The movable clutch member is spring pressed toward the fixed clutch member through a spring 24, 55 and a lever 25 is provided with a yoke to engage an annular groove in the movable clutch member for normally holding the movable clutch member free of engagement with the fixed clutch member. The lever is 60 pivotally supported on the main frame and has a lateral extension 26 adapted to overlie the end of a trip bar 27, which latter is notched or cutaway for a portion of the upper end, as at 28. The trip bar, which is 65 pivotally connected to the main frame is

connected at the lower end to a rod 29, which in turn is connected to a projection 30 extending upwardly from a plate 31, pivotally mounted at 32 on the edge of the operating table adjacent the anvil. 70

The clutch is designed to be automatically disengaged at each revolution, it being provided for this purpose with a block 33 slidably mounted in a recess in the block supporting lever 25. This block 33 has one end 75 arranged to contact with the lever 25, and the opposite end adapted to be engaged by a wedge 34 secured on and movable with the fixed clutch member 23. In each revolution of the shaft therefor, and at an appropriate 80 period in such revolution, the clutch wedge member 34 moves the block 33 laterally to force the lever 25 to a position to disengage the clutch. As the lever 25 is moved by the block 33, the lateral extension 26 of said 85 lever is moved to a position above the lower wall of the notch 28 of the bar 27, whereupon the spring 35 between said bar 27 and the frame draws the notched end of said bar beneath the lever extension 26 and holds the 90 clutch open. In order that the shaft 3 may be stopped at the same point of each revolution, there is provided a braking element including a brake drum 36 forming an integral part of a cam 37 secured upon the shaft. 95 This cam has a projection 38 adapted to engage a spring 39 secured on the frame and overlying the cam. To the free terminal of this spring is connected a leather strip 40, which strip overlies the brake drum 36, 100 with its opposite end fixed to the frame. As the cam projection 38 depresses the spring 39, it will tighten the brake band 40 about the drum 36, checking the movement of the shaft 3 and causing it to stop at the same 105 point in each revolution.

As previously explained, the parts of both the male and female sections of the fastener, that is the two metal elements making up the section, are separately applied, one to 110 one side of the fabric, as a glove and projecting through a hole therein, as indicated at 41, the other part being applied over such first part and to the opposite side of the fabric. This operation is performed by the 115 operator, who then places the assembled fastener parts and fabric or glove over the anvil, as indicated, holding the article in this position with two fingers pressing the article against the anvil, well below the upper 120 end thereof. As an essential feature of the safeguarding principle of the invention, the respective parts of the fastener sections are arranged in separate hopper containers, as shown, from which they are quickly and 125 conveniently removed by the operator as desired. These hoppers are arranged in pairs on a rotating base mounted on the operative table, one pair for the parts of one fastener section and the other pair for the 130

parts of the other section. As it is customary for the operator to apply all the fastener sections of like character to the gloves in hand, and then apply all the fastener sections of the other kind, it is necessary to describe the use of these containers for but one fastener section. These containers of one pair, as 42 and 43 contain the respective parts of such particular fastener section, the 5 hopper 42 containing the main part and the hopper 43 containing the washer or clamping part. Now it is to be noted that the hoppers are so mounted that the free edge of the discharge lip of hopper 42 is immediately adjacent and above the upper edge 10 of the plate 31, which is connected to the trip bar as previously described.

The edge of this plate adjacent the discharge lip of the hopper 43 is cutaway at 15 44 to avoid engaging the plate in removing 20 a fastener part from such hopper.

We will assume the machine set, a glove fastener section assembled in the glove opening, and the parts on the anvil, as indicated in Fig. 1. Now as the operator reaches with the right hand, the left hand 25 means while holding the glove and parts on the anvil, to get the main part from the hopper 42 for the next hole in the glove, 30 the plate 31 is rocked, the trip rod moved sufficiently to let the lever 25 move to cause clutch cooperation, the shaft 3 is rotated, the carrier moved to position the selected die rod beneath the plunger 5, and the latter 35 operated by the cam 4 to force said die rod down and complete the setting of the fastener section on the anvil. All this occurs practically as the operator is withdrawing the initial part for the next fastener 40 section, thus taking her hand entirely out of the way of the die rod and avoiding possible injury. Having placed the initial part taken from the hopper 42 in the glove hole, the operator reaches into 45 the hopper lip for the other or second part of such fastener section, but as the plate 31 is cutaway at 44 adjacent this hopper, no machine operation occurs.

Of course the base on which the pairs of 50 containers are mounted is simply reversed when fastener parts from the other containers are desired, the operation with such parts being identical with that just described.

The die carrier is moved by a lever connected with such carrier by a spring as 15, so that if automatic operation of the machine should take place while the operator's hand is above the anvil, the movement of the die 55 carrier will be arrested by the hand, and no movement of the die rod will follow the movement of the plunger. Thus injury under such, ordinarily very infrequent conditions is avoided.

The die carrier may be temporarily se-

cured in operative position by spring arms 45 secured to the adjacent frame bar and underlying the carrier block, with offsets 46 over which the block rides when in operative position to thus temporarily hold the 70 carrier set with relation to the plunger.

What is claimed, is:

1. An automatically operated glove fastener upsetting machine, combined with containers for the fastener parts, and means 75 for releasing the machine for automatic operation while removing a part from one of said containers.

2. An automatically operated glove fastener upsetting machine, including a plunger 80 operated die rod, combined with separate containers for the glove fastener parts, and means for releasing the machine for automatic operation in withdrawing such part from one of the containers. 85

3. A machine for upsetting the parts of glove fastener members, including a plunger operated die rod, a trip for holding the machine against operation, containers for the parts of such fastener member, and means 90 operated in withdrawing a part from one of such containers for actuating the trip.

4. A machine for upsetting the parts of glove fastener members, including a plunger operated rod, means for actuating the 95 machine, a trip for holding the machine against operation, a container for one of the parts of such fastener member, and a plate adapted to be rocked and actuate the trip in withdrawing a part from such container. 100

5. The combination of a glove fastener upsetting machine, a trip for holding said machine against operation, a plate for operating the trip, and a container for one part of such glove fastener arranged adjacent the 105 plate to permit operation of the plate in withdrawing a part from such container.

6. A glove fastener upsetting machine, including a driven shaft, a cam carried thereby, a plunger operated by the cam, a die 110 carrier mounted for movement to and from a position beneath the plunger, means operated by the shaft for moving the carrier, and die rods adjustably mounted on said carrier for selective arrangement with relation 115 to said plunger.

7. A glove fastener upsetting machine including a driven shaft, a plunger, a die carrier mounted for movement to and from a position beneath the plunger, and a single 120 shaft for operating the plunger and die carrier, said carrier having a plurality of die rods mounted thereon for selective arrangement.

8. A glove fastener upsetting machine including a driven shaft, a plunger, a die carrier mounted for movement to and from a position beneath the plunger, and a single 125 shaft for operating the plunger and die carrier, said die carrier including a rotatable 130

- table, die rods arranged in said table, and means for securing the table in adjusted position for selective arrangement of the die rods.
5. 9. The combination with an automatically operated glove fastener upsetting machine normally locked against operation, of a container for the fastener parts located adjacent the machine, and means for releasing the 10 lock to permit automatic operation of the machine while removing a part from said container.
10. In a glove fastener upsetting machine, an anvil, a plunger, a die carrier operative 15 to and from a position between the plunger and anvil, and means to permit yielding of the die carrier in the event of an obstruction on the anvil exceeding the normal height of the glove fastener parts, the said yielding 20 of the die carrier being permitted without interfering with the machine movements and serving to avoid pinching the obstruction in the movement of the plunger.
11. In a glove fastener upsetting machine, 25 an anvil, a plunger, a die carrier movable to and from a position between the plunger and anvil, and a plurality of dies mounted in said die carrier and adapted for manual selective positioning for cooperation with 30 the plunger in the movement of the carrier.
12. In a glove fastener upsetting machine, an anvil, a plunger, a die carrier movable to and from a position between the plunger and anvil, and a plurality of dies mounted 35 in said die carrier and adapted for manual selective positioning for cooperation with the plunger in the movement of the carrier, a machine driven member to operate the die carrier, and a spring connecting said member with the carrier to permit of a less than 40 normal movement of the carrier without interfering with the movement of said member.
13. In a glove fastener upsetting machine, an anvil, a plunger, a die carrier operative 45 to and from a determinate position between the plunger and anvil, the die in said carrier adapted in said determinate position of the die carrier to be in line with the plunger and anvil and to be operated upon by the plunger, and means to permit the die carrier to 50 be arrested short of its determinate position by an obstruction in its path of movement above the anvil without interfering with the other machine movements, whereby through such arresting of the die carrier, the die 55 is held beyond the reach of the plunger, and the movement of the latter cannot affect the object on the anvil.

In testimony whereof I affix my signature.
THOMAS F. MORRIS.
